UNITED STATES PATENT OFFICE.

EDWIN G. VAN WIE AND RANSOM W. DAVENPORT, OF DETROIT, MICHIGAN, ASSIGNEES
TO DETROIT STOVE WORKS, OF DETROIT, MICHIGAN, A CORPORATION OF MICHIGAN.

ELECTRICAL HEATING UNIT.

1,142,862.

Specification of Letters Patent. Patented June 15, 1915.

Application filed November 25, 1912. Serial No. 733,512.

To all whom it may concern:

Be it known that we, EDWIN G. VAN WIE and RANSOM W. DAVENPORT, citizens of the United States of America, residing at Detroit, in the county of Wayne and State of Michigan, have invented certain new and useful Improvements in Electrical Heating Units, of which the following is a specification, reference being had therein to the accompanying drawings.

The invention relates to electrical heating units, and particularly to that type in which the heat-developing resistor is wound spirally upon a supporting core of insulating material.

It is one of the objects of the invention to obtain a construction which will be more efficient in heating where the object to be heated is arranged on one side only of the unit.

It is a further object to facilitate the attachment and detachment of the units so that they may be removed or replaced when necessary.

A further object is to rigidly support the resistor without conducting any heat therefrom at points of support, thereby facilitating the quick heating of said resistor.

In the drawings: Figure 1 is a perspective view of the unit. Fig. 2 is a cross section through an oven, showing the arrangement of the heating units therein. Fig. 3 is a cross section through one of the units.

It is usual with heating units of the type to which my invention belongs to employ a core of round section for supporting the spiral resistor. This interposes the core between one-half of the surface of the resistor and the work which is to be heated, and thereby reduces the heating efficiency.

With my improved construction, in place of a core of round cross section, I employ a triangular shaped core, so that the direct radiation from two-thirds of the conductor is in the same general direction, while only one-third is shielded by the core.

As shown in detail, A is a core member formed of insulating material or of metal having an insulating facing. This core member is preferably of a Y-shaped cross section forming projecting ridges B spaced from each other at substantially equal angles.

C is the resistor in the form of a wire or

ribbon, and which is spirally wound upon 55 the core A, being in contact with the several ribs and assuming a triangular shape. D is a head at one end of the core member A, upon which is mounted the terminal contacts E and E' secured to suitable insulator 60 supports and connected with the ends of the resistor.

In use, the units are arranged as shown in Fig. 2, with one of the sides of the triangle parallel with the oven wall or heat-reflecting 65 surface F, while the other two sides of the triangle are in opposite oblique positions. This will permit direct radiation of heat from the resistor on the two sides G and G' without any shielding from the core, while 70 the third side G², which is behind the core, will radiate heat against the reflecting surface F, which will distribute it downward. Thus two-thirds of the direct radiation from 75 the resistor is available and passes into the work, while the radiation from the third side is reflected back to increase the effect.

When the unit is inserted in an oven or other position where it is to be used, the terminal contacts E and E' will engage co-operating 80 socket contact members in the stationary part, which will automatically complete the electric circuit.

What we claim as our invention is:

1. An electrically heating unit comprising 85 a supporting frame formed with an opening and a boss surrounding the opening which projects beyond the frame, a member received within said boss said member being formed with radially extending longitudinally disposed ribs, and a coil constituting a resistor wound about the member and contacting with the edges of the ribs, the contact of the resistor with the ribs bending the wire of which the resistor is formed to produce triangular windings. 90

2. The combination with a casing having a top bottom and sides of an electrical heating element insertible within the casing immediately beneath the top of the same, said element having radially extending longitudinally disposed ribs, one of said ribs being of greater width than the remaining ribs, a coil constituting a resistor wound about the member and contacting with the edges of 105 the ribs, the member being so supported that in end elevation the longer rib is disposed vertically, the windings thus producing a

short horizontal heating surface and converging obliquely disposed heating surfaces of greater length than said horizontal heating surfaces whereby heat will radiate directly from the resistor on two sides and without shielding from the member, the heat radiating from the third side being reflected downwardly by the top of the casing.

In testimony whereof we affix our signatures in presence of two witnesses.

EDWIN G. VAN WIE,
RANSOM W. DAVENPORT.
